UNITED STATES PATENT OFFICE.

GEORGE H. MYRICK, OF CHICAGO, ILLINOIS, ASSIGNOR TO CAPITAL ELECTRIC COMPANY, OF CHICAGO, ILLINOIS, A CORPORATION OF ILLINOIS.

WASHING-MACHINE.

1,169,420.

Specification of Letters Patent. Patented Jan. 25, 1916.

Application filed August 4, 1913. Serial No. 782,785.

To all whom it may concern:

Be it known that I, GEORGE H. MYRICK, a citizen of the United States, residing at Chicago, in the county of Cook and State of Illinois, have invented a certain new and useful Improvement in Washing-Machines, of which the following is a full, clear, concise, and exact description, reference being had to the accompanying drawings, forming 10 a part of this specification.

My invention relates to an improved form of washing machine in which the articles to be washed are moved in the solution by means of which they are washed by the 15 projection into and through said articles of a stream of the solution; and in the preferred embodiment of my invention I provide a rotary cylinder for containing the articles to be washed, such as clothing, 20 against which the stream of solution, as water and soap, is projected tangentially or nearly so, by means of a fan or screw propeller. This fan is preferably electrically-driven, and the motor thus employed may 25 be used to also drive a wringer, if desired. The cylinder employed to contain the clothing to be washed is of openwork construction so that the water and soap solution projected against the side of the cylinder not 30 only imparts to it a rotary motion, but the solution is also projected through the walls of the cylinder and into and through the clothing, thus agitating the same and greatly assisting in the separation from the clothing 35 of the dirt contained in it.

The several drawings illustrating my invention are as follows.

Figure 1 is a vertical sectional view taken transversely of the horizontal axis of the 40 cylinder of the machine, and shows all of the parts in assembled relation; Fig. 2 is a vertical sectional view taken longitudinally through the axis of the cylinder along the line 2—2 of Fig. 1; Fig. 3 shows, in end 45 view, a modified construction of the machine in which the motor, instead of being disposed beneath the tank of the machine, is placed upon the top thereof in a position to drive a wringer, if desired; Fig. 4 shows, 50 in top view, another modified construction of my improved washing machine, in which the cylinder for receiving the clothes to be washed is supported to rotate upon a vertical axis, and Fig. 5 is a side view of the parts 55 shown in Fig. 4.

Similar numerals refer to similar parts throughout the several views.

As shown in Figs. 1 and 2, the washing machine consists of a tank 1 having a hinged cover 2 and provided at its ends with bearings 3 and 4 for the journals 5 and 6 of the cylinder 7. The cylinder 7 is preferably composed of a metal framework consisting of a plurality of arms 8 and end rings 9 and 10, over and to which wire netting is secured 60 of small enough mesh to prevent the smallest articles to be washed passing through it, and of large enough mesh to permit water to freely pass into and out from the cylinder. The cylinder is provided with a hinged door 11 secured in place by a suitable catch 12 so 65 that the clothing may be introduced into the cylinder and taken therefrom when desired. The bottom of the tank 1, at the left-hand side, as indicated in Figs. 1 and 2, is rounded 70 so as to conform somewhat to the shape of the outer surface of the cylinder 7, and at the right-hand side the bottom of the tank is separated from the cylinder to receive the tubular housing 13 which contains a horizontally-disposed fan or screw propeller 14 75 secured to the upper end of a vertical shaft 15 extending downward through a stuffing box 16 in the bottom of the housing 13 and driven by means of a motor 17 secured to a bracket 18 extending downward from the bottom of the tank 1. The tank and parts 80 carried thereby are supported in any desired position by means of legs 19 and 20.

The tank 1 is provided at its upper right-hand portion with a shield or deflector 21, by means of which the soap-and-water solution is directed from the fan 14 over the top 90 of the cylinder and down upon the left-hand side thereof.

As a result of the construction described, when the clothing to be washed has been placed in the cylinder 7 and the soap-and-water solution has been placed in the tank 1 to the proper depth, preferably to the top 100 of the cylinder, the motor 17 is started and as it has a direction of motion such as to rotate the fan 14 to project the water contained in the housing 13 upwardly, this projects the soap-and-water solution upward 105 against the right-hand side of the cylinder 7, with the result that the cylinder is rotated by the impact of the solution against the same. The wire netting of the cylinder 110 permits a large part of the water to project

into and through the clothing to be washed, with the result that the clothing is manipulated mechanically by the water thus projected, which becomes thus an effective 5 factor in washing the clothes.

The rotation of the cylinder 7 and the stream of water from the fan 14 move the clothing in the cylinder toward the upper part thereof and over to the other side. The 10 water and soap solution in considerable part is projected vertically and strikes the deflector 21 and is turned so as to pass over the cylinder to the left and thus downward upon the left hand side of the cylinder; re- 15 turning along the bottom of the tank 1 to the outside of the housing 13 which it enters through the openings 22 provided therefor, so that it may again be engaged by the fan. The remainder of the solution, or that which 20 entered the cylinder as it was projected from fan 14, is drawn out of the cylinder at the left hand side thereof and toward the openings 22 through which fluid is supplied to the fan 14. Thus, when the clothes are 25 brought around by the cylinder into the stream of water formed by the fan 14, a portion of the water is driven through the fibers of the clothing and thus dislodges the dirt contained therein. When the clothing 30 is carried around to the left-hand side of the cylinder, the water is again drawn through the fibers of the cloth in order to leave the cylinder and travel to the bottom of the tank to enter the openings 22. There 35 are thus three actions tending to wash the clothes. First the water driven through the clothing as the same is brought in front of the fan. Second, the water is again drawn through the clothing at the left-hand thereof 40 and toward the fan 14. Third, there is also a general rotation and agitation of the water which aids materially in the washing of the clothes. Thus a constant circulation is estab- 45 lished inside of the tank 1 which effectually rotates the cylinder 7 and at the same time washes the clothes.

In the modified construction shown in Fig. 3, the disposition of the fan 14^a in the tank 1^a is substantially the same as that 50 shown and described in Fig. 1, the difference being that the fan is secured to the lower end of a shaft 15^a extending upwardly in a slightly oblique direction through the top of the tank, where it has secured to its upper 55 end one member 23 of a jaw clutch, the other member 24 of which is mounted to slide upon the lower end of the shaft of the motor 17^a. An operating handle 25 controlling a lever 26 is provided to throw the 60 upper member 24 of the jaw clutch into engagement with the lower member or not, as desired. The upper end of the shaft of the motor 17^a has similarly secured to it in sliding relation, the lower member 27 of a second jaw clutch, the upper member 28 of

which is secured to a pulley 29, from which a belt 30 extends to a pulley 31 secured to the driving shaft of a wringer 32 mounted upon the tank 1^a. Thus, by means of the jaw clutches described, either the wringer 70 or the fan may be operated as desired, or, if preferred, both may be operated together by means of the motor 17^a. The operation of the fan 14^a in this modified construction is substantially the same in rotating the 75 cylinder 7^a and washing the clothes as already described in connection with the construction shown in Figs. 1 and 2.

In the modified construction shown in Figs. 4 and 5, the cylinder 7^b is similar to 80 the cylinders 7 and 7^a above-referred to, with the exception that the door 11^b for permitting access to the cylinder is secured to the upper end of the cylinder instead of to its cylindrical side. The cylinder 7^b is 85 mounted in bearings formed in the top and bottom of the tank 1^b, which tank is substantially the same as the tank 1 shown in Fig. 1 turned upon one end, the only difference being that for the construction shown 90 in Fig. 5 the sides are continuous and the door 2^b provided for giving access to the cylinder is hinged to the top of the tank in the construction shown in Fig. 5, which is equal to the end of the construction shown 95 in Fig. 1.

For the construction shown in Figs. 4 and 5 the motor 17^b is mounted upon a bracket 18^b disposed at one side of the tank 1^b and substantially half way between the top and bottom of the tank. The motor has secured to it a fan working in a housing in a manner similar to that shown and described for the fan 14 above, and the soap-and-water solution is acted upon by the fan 105 in substantially the same manner described above, with the exception that in the present case the water circulates in horizontal planes instead of inverted planes as is the case in the constructions shown in Figs. 1, 2 and 3. 110 No special deflector is required in connection with this modified construction, since the side walls of the tank, being continuous and without break, may be readily conformed to direct the solution without auxiliary 115 means.

While I have referred to an electric motor as the preferred form for operating my machine, it will be understood that it is not essential that this type of motor mechanism 120 be used, as any motor mechanism may be employed that may be desirable, the only requirement being that the fan secured to the shaft shall in each case be driven by suitable motor mechanism, either directly or indirectly, so that the solution in the tank shall be given sufficient velocity to rotate the cylinder and wash the clothing. Furthermore, it will be understood that any desired mechanism may be employed for driving the 125 130

wringer from the motor, and if desired for reversing the direction of the rotation of the wringer, and that I do not limit myself to the precise construction indicated.

5 In carrying out my invention, I do not limit myself to any precise relation of parts between the tank, the cylinder and the fan, but, on the other hand, I may employ many different relations and conformations of 10 these parts, the only requirement being that the solution shall be projected by the fan against the cylinder with such velocity that it shall properly rotate the cylinder and serve by its mechanical action to at least 15 in part wash the clothing.

What I claim is:

1. A machine for washing fabrics comprising in combination an openwork cylindrical fabric container, a propeller disposed 20 on one side of the axis of the fabric container, a deflector disposed on the side of the container axis opposite the propeller, a tank inclosing and supporting the fabric container, propeller and deflector, said tank 25 having its walls lying immediately adjacent to the ends and cylindrical surface of the fabric container and adapted to contain washing solution to a depth immersing the propeller, deflector and fabric container, 30 said propeller rotatable about an axis substantially normal to the axis of the fabric container and adapted when operated to project a continuous stream of washing solution through the fabric container and 35 against the same to cause rotation thereof, and means for rotating said propeller.

2. A machine for washing fabrics comprising in combination an openwork cylindrical fabric container, a propeller disposed

on one side of the fabric container, a tank 40 inclosing and supporting the fabric container and propeller, said tank having its walls lying immediately adjacent to the cylindrical surface of the fabric container and adapted to contain washing solution to a 45 depth immersing the propeller and fabric container, said propeller rotatable about an axis substantially normal to the axis of the fabric container and adapted when operated to project a continuous stream of washing 50 solution toward and through the fabric container, and means for rotating said propeller.

3. In a device of the class described, the combination of an openwork cylindrical container mounted upon a substantially horizontal axis, a tank inclosing and supporting the cylindrical container, said tank having its walls lying immediately adjacent to the cylindrical surface of the container and 55 adapted to contain washing solution, a propeller disposed in the bottom of the tank 60 rotatable around an axis substantially at right angles to the axis of the cylindrical container and arranged when operated to 65 project a continuous stream of washing solution against and through the cylindrical container, and a deflector supported by the tank at the top thereof, said deflector disposed adjacent to the cylindrical surface of the container and in a line with the axis of the aforesaid propeller.

In witness whereof, I hereunto subscribe my name this 23rd day of July, A. D., 1913.

GEORGE H. MYRICK.
